INVENTOR.

Gilbert Bakke
BY
Thomas Donnelly
ATTORNEY.

UNITED STATES PATENT OFFICE.

GILBERT BAKKE, OF DETROIT, MICHIGAN.

SPARK INTENSIFIER.

Application filed October 17, 1924. Serial No. 744,127.

To all whom it may concern:

Be it known that I, GILBERT BAKKE, a citizen of the United States, residing at Detroit, in the county of Wayne and State of Michigan, have invented a new and useful Improvement in a Spark Intensifier, of which the following is a specification.

My invention relates to a new and useful improvement in a spark intensifier, 10 adapted for use with spark plugs for intensifying the spark which is obtained at the sparking electrodes which are used for igniting the combustible material surrounding them. In order to intensify the spark 15 at the sparking points I have provided an insulating member which is adapted to insulate the metal eyelet which is attached to the cable and which embraces the stem of the spark plug and prevents contact of the 20 eyelet with any metal portion of the spark plug so that the electrical energy delivered to the eyelet through the cable from the source of electrical energy is forced to jump a gap in order to reach the metal portion of 25 the spark plug.

I am aware that intensifiers of this class have been constructed, but the present invention is intended to present a novel arrangement for accomplishing the intensifying 30 of the spark. The present invention is adapted for mounting on the outer portion of the electrode very easily and quickly and is so constructed as to be adaptable for use with various kinds of cables, the intensifier 35 being loose from the cable and not permanently attached thereto as are some intensifiers of which I am aware.

It is an object of the invention to provide 40 an intensifier which will be simple in structure, economical of manufacture and highly efficient in use.

Another object of the invention is the provision of an intensifier consisting of separate parts which may be mounted on the 45 outer portion of the spark plug electrode so as to securely insulate the eyelet connected to the cable supplying the energy from all contact with any metal portion of the plug.

Another object of the invention is the 50 provision of a spark plug intensifier formed from a pair of parts, one of said parts having a neck for entering the eyelet of the cable and provided with a plurality of radial slots, communicating with the bore of 55 the neck.

Other objects will appear hereinafter.

The invention consists in the combination and arrangement of parts hereinafter described and claimed.

The invention will be best understood 60 from a reference to the accompanying drawings which form a part of this specification and in which,

Fig. 1 is a side elevational view of the invention attached to a spark plug, 65

Fig. 2 is a fragmentary central section view of Fig. 1,

Fig. 3 is a perspective view of one of the parts used in the invention.

The invention is shown in Fig. 1 and 70 Fig. 2 as applied to a conventional spark plug 7 having the porcelain portion 8 through which is projected the metallic electrode 9, the upper end of which is threaded. A nut 10 is threaded on the electrode 9 and 75 engages the washer 11.

An insulating disk 12, made from fibre or other suitable non conducting material is provided with a central opening through which the electrode 9 may project. Projecting outwardly from one face of the disk, and preferably made integral therewith from some non conducting material is a neck 13 which is provided with a plurality of radially extending slots 14 which serve to divide the neck into a plurality of sections. The disk 12 is adapted for seating on the electrode 9, as shown in Fig. 1 and Fig. 2, the neck being projected outwardly toward the end of the electrode which is exterior of 90 the spark plug proper. The cable 19 which is connected to the battery or other source of electrical energy is provided with a metallic clip 18 having an eyelet 17 formed at the end, adapted for being mounted on the neck 13 in embracing relation. A fibre or non conducting washer 15 is mounted on the electrode so as to insulate the eyelet from the metal nut 16 which is threaded on the electrode and serves to bind the washer 100 firmly against the eyelet.

With this structure the eyelet is insulated from the metal of the spark plug and no direct contact of the eyelet with the metal of the spark plug is possible. The current flowing into the eyelet is forced to jump the gap separating its edges from the electrode 9, when a sufficient potential is built up to cause the current to jump the gap. It will be noted that this jumping of the current is radially of the electrode 9 and directly toward the electrode 110

itself. I am aware that some of the intensifiers cause the spark to jump through openings provided in the washer 15, so that the current passes from the eyelet to the nut 16 and then to the electrode 9. The direct jumping of the current to the electrode is desirable as this form of intensifier proves more efficient than one wherein there is an indirect jump of the current.

10 While I have illustrated and described the preferred form of structure I do not wish to limit myself to the precise details set forth, but desire to avail myself of such variations and modifications as come within 15 the scope of the appended claims.

Having thus described my invention what I claim as new and desire to secure by Letters Patent is:

1. An intensifier of the class described comprising a non-conducting disk; a neck 20 projecting outwardly from one face of said disk, and having a plurality of radially extending slots formed therein, said disk and neck having a centrally disposed opening 25 formed therein, said slots communicating with the opening in said neck; and a non-conducting washer adapted for mounting on said neck, said washer having an opening formed centrally therein for the reception 30 of said neck.

2. An intensifier of the class described comprising a disk formed from some non-conducting material and having a centrally disposed opening formed in it; a neck 35 formed from non-conducting material, projecting outwardly from one face of said disk, concentrically of the opening in said

disk, said neck having an opening formed therein in registration with the opening in said disk, said neck having a plurality of radially projecting slots formed therein communicating with the opening passing through said neck; and a non-conducting washer adapted for seating on said neck in 40 embracing relation.

3. An intensifier of the class described adapted for use with a spark plug having a centrally disposed electrode adapted for connection with a metallic cable eyelet, and threaded at its upper end for the reception 50 of a binding nut, comprising a non-conducting disk adapted for mounting on said electrode in embracing relation, said disk being provided with an opening for the reception of said electrode; a neck projecting outwardly from one face of said disk, said neck being concentric with said disk and having an opening in it for the reception of said electrode, said neck being formed in sections and having a plurality of radially extending slots separating said sections, said neck being of sufficient size 55 for the reception of said eyelet about it in embracing relation; and a non-conducting washer, having a centrally disposed opening 60 for the reception of said neck said washer being adapted for clamping engagement against said eyelet for retaining the same in assembled position on said neck, upon the threading of the binding nut used with 65 the upper end of said electrode.

In testimony whereof I have signed the foregoing.

GILBERT BAKKE.
